BALANCING MACHINE

John Leonard Taylor, Milwaukee, Wis.; Grace Brindley Taylor, executrix of said John Leonard Taylor, deceased

Application November 3, 1933, Serial No. 696,559

13 Claims. (Cl. 73—51)

- The present invention relates to balancing mechanism for rotative bodies, and an object of the invention is to generally improve the construction and operation of such mechanism.
- 5 A further object is to provide novel mechanism for balancing rotative bodies.
- Further objects are to provide the following:
- Mechanism for performing dynamic balancing including a bearing arranged to support a work piece substantially rigidly, but to permit slight deformation or deflection under centrifugal forces developed by rotation of unbalanced weight in the work piece;
- 10 A machine including a plurality of such bearings arranged to coact with a work piece at spaced intervals;
- A bearing having a portion arranged to be moved by deformations or deflections of a work piece;
- 15 Such a bearing in which said means includes an electric circuit and circuit controlling means actuated by movement of said portion;
- A balancing machine including such a bearing, an electric circuit, and indicating means connected with said circuit and responsive to said circuit controlling means;
- 20 Such a machine having a plurality of such bearings spaced at desired points in the length of a work piece, and indicating means responsive to the circuit controlling means in said bearings;
- 25 Indicating means for indicating the position of a work piece when movement of the movable portion of one of said bearings takes place, including a rotative member operating synchronously with said work piece, and means for illuminating said member periodically in accordance with movements of said movable portion;
- 30 Such indicating means including a dial rotating synchronously with the work piece and an index arranged to be fixed relatively to the dial at the instant deflection takes place in the work piece;
- 35 Mechanism for automatically compensating for lag occurring in the above outlined indicating means;
- The combination of mechanism as outlined above with mechanism for correcting the unbalance of a work piece without removing it from the testing apparatus;
- 40 50 Mechanism for performing certain calculations required in determining the amount of unbalance in a work piece.
- Expedients for the convenient construction and operation of the above apparatus.
- 45 55 The mechanisms used for the attainment of

these objects are illustrated in the annexed drawings in which:

Fig. 1 is a front elevation of an illustrative machine arranged for the practice of the invention, parts being broken away for a better showing of certain other parts.

Similar reference characters have been applied to the same parts throughout the drawings and the following specification.

30 It is well known that rotative parts, particularly such as are characterized by considerable length, unless accurately balanced substantially continuously throughout such length, are subject to distortion under the centrifugal effects 35 of unbalanced weight when rotated at high speed. Such a piece may be perfectly statically balanced, and perfectly dynamically balanced in the ordinary manner, and still contain unbalanced weight such as will produce such stresses 40 and distortion when the piece is placed in service.

The present invention operates by rotating the piece under conditions approximating those under which it operates in service, and determining, from the distortions which take place, the 45 locations and magnitudes of the unbalanced weights in the piece, whereupon they can be eliminated and the tendency toward distortion destroyed.

In balancing with the disclosed apparatus the 50 work piece is supported at a plurality of axially spaced points and maintained substantially positively in alignment at each of said points while it is rotated at a speed preferably in the neighborhood of that at which it will be run in service, although any speed high enough to develop 55 substantial centrifugal forces in the piece would serve the purpose, and there is no objection to speeds higher than the service speeds so long as they are within the capacity of the apparatus used. The piece is not allowed to vibrate substantially as a whole, contrary to the usual practice in dynamic balancing, but is held in alignment by substantial pressure at each of the spaced points, and while the piece is rotating 60 the pressure is reduced at these points, one at a time, so that the piece may distort at each point. The position of the piece at which distortion 65 takes place is observed by any suitable mechanism, and the pressure necessary at each point 70 to prevent the distortion is noted. From these data in conjunction with the known speed of rotation of the work piece the value of the unbalanced weights or "heavy spots" in the piece may be readily calculated, as well as the amount 75 of material to be removed at each determined

location in order to put the piece in what might be termed "continuous" dynamic balance.

If the piece has been previously balanced by supporting it at its ends, assuming it to be rigid, and correcting it until there is no tendency to 5 displacement of the ends, the piece may be said in one sense to be dynamically balanced, but the piece is not rigid, and there will still exist heavy spots which are axially spaced from each other, but so located angularly that they balance each 10 other statically or dynamically when the piece is tested as above at moderate speeds. At high speeds, however, they do not balance each other since because of their axial displacement, they cause a distortion or "whip" of the shaft which 15 renders further testing by the outlined method impossible. The piece is accordingly not balanced, and when so distorted will cause serious vibration and wear on its bearings, and other well known undesirable results. 20

By utilizing such distortions to locate these axially spaced heavy spots, they can be discovered and eliminated, whereupon the piece will be in a true state of dynamic balance, and will have superior operating characteristics hereto- 25 fore unknown.

As seen in the drawings the present mechanism includes a bed or base generically designated by numeral 1, Figs. 1 and 2, carrying a tail-stock 2, and a head-stock 3, the part to be 30 tested, in the present instance indicated as a crank-shaft 4, being supported from base 1 between head-stock 3 and tail-stock 2 in a plurality of bearing units generically designated by numeral 5. Each of the bearing elements supports 35 in the present instance one of the journals of the shaft 4 through a plurality of rolls 6, 7, and 8, rolls 6 and 7 being substantially rigidly fixed in position, and roll 8 being capable of movement radially of the shaft journal 9. This move- 40 ment of roll 8 is suitably resisted, and actuates, through intervening mechanism described below, an electrical contacting mechanism generically designated by numeral 10, the resulting impulses affecting an indicating device generically design- 45 ated by numeral 11, which serves to indicate the angular position of the shaft or work piece at the instant that distortion of the piece causing movement of roll 8 takes place. The amount of resistance opposed to movement of roll 8 50 may be regulated by means of a cap, grip, or the like 12 which may be provided with graduations for directly indicating the force exerted. Rotation may be imparted to the work piece through head-stock 3 from a motor 13, and current may 55 be supplied for the operation of indicator 11 by means of a generator 14 also driven from motor 13. The speed of rotation of the work piece is indicated at a suitable tachometer or other speed indicating device 15. 60

The specific details of the mechanism may be varied to a considerable extent, but for purposes of illustration a complete operative structure has been disclosed which will be completely described. It is to be understood, however, that nothing in the specific embodiment shown and described is intended to limit the protection solicited, and that the invention is not limited in any manner except as defined by the subjoined claims. 65

As illustrated in Figs. 1 and 2, base 1 comprises a boxlike structure suitably ribbed for stiffness and stability, and provided with openings 16 for access to the interior thereof, and having a bracket 17 for supporting motor 13 and generator 70 75

14. The base is provided with guide portions 18 and 19 running lengthwise thereof, and ribs or shelf portions 20 and 21 extend forwardly and rearwardly respectively immediately below the 5 guides. The guides are for the purpose of guiding tail-stock 2 and bearings 5 to various positions on the base to accommodate work pieces of different sizes, the guides in the present instance being of dove-tail cross section as shown 10 in Fig. 2 to interlock with suitable portions of the other elements.

The clamping means used on the tail-stock is identical with that used on the several bearing elements 5, so a description of the bearing 15 clamps will suffice for all. As seen in Fig. 2, the bearing elements have downwardly projecting portions or feet 22 and 23, having downwardly extending members 24 and 25 respectively, these members being provided with angular guiding surfaces 26 and 27 cooperating with complementary surfaces on guides 18 and 19. The surfaces are maintained in their correct 20 relation by clamping elements 28 and 29 urged into position by bolts or the like 30 and 31 against angular surfaces 32 and 33 respectively on guides 25 18 and 19, the clamps also engaging surfaces 34 and 35 on portions 22 and 23 so as to urge the bearing member 5 firmly down on the guides 18 and 19 when bolts 30 and 31 are tightened. 30 A similar arrangement may be used if desired to fasten head-stock 3 down on the base, but, since it is not necessary to change the position of the head-stock, it may if desired be bolted permanently to the base by means of bolts or 35 the like 36—36.

The machine is preferably arranged for the accommodation of a variety of sizes and types of work pieces, the tail-stock 2 being movable, and the bearing members 5 being movable, and 40 removable; so that as many bearings may be used as there are journals on the work piece, the remaining bearings being removed and stored. The particular form of guides 18 and 19 facilitates removal and replacement of the bearing 45 members, since, when the clamps 28 and 29 are loosened, the bearing members can be lifted directly off the base 1 with only a slight backward movement necessitated by the slope of the surfaces 26 and 27. In the testing of cylindrical or other objects having no well defined 50 journals as many bearings as prove to be necessary or desirable may be applied at various points along the length of the piece. Examples of such work pieces would include drive shafts, calendar 55 rolls, and certain types of rotors for electrical machinery.

Provision is made for convenience in setting up a work piece to be tested. Movable rolls 8 are carried through intermediate elements described below by brackets 37 which may swing about suitable pivots to permit the work piece to be placed in position as in a lathe between centers 38, on tail-stock 2, and 39, (Fig. 3) on head-stock 3. Rolls 6, 7, and 8 are then advanced into contacting relation to the work piece and the centers withdrawn by suitable mechanism described more particularly below, leaving the piece supported on the rolls engaging its own journals. The piece is then tested and corrected 65 if desired as above outlined after which the rolls 8 are withdrawn and the piece lifted out of the machine. A similar piece may then be placed in the machine, and rolls 8 engaged with it without the necessity for going through the centering process again.

It is to be noted that the supporting means carrying rolls 7 are disposed slightly forwardly of a vertical radius of journal 9. The work piece is therefore stably supported in the machine even when rolls 8 are withdrawn, since the tendency is for it to move rearwardly against rolls 6. This feature facilitates the removal of material from the piece as described below, since the rolls 6 and 7 are rigidly supported, and the support of the work-piece against the cutting 10 reactions is furnished by these rolls, and not by the yielding rolls 8, the piece being rigidly supported on rolls 6 and 7 without dependence on roll 8.

Tail-stock 2 may be of any suitable or desired 15 type, but in the present instance it has a body portion 40 provided with a screw actuated or other suitable ram or plunger 41 carrying above-mentioned center 38, the body being provided with suitable means such as a lever 42 for clamping 20 the plunger in desired positions.

Center 38 is provided with a small flat surface at its tip as shown in Fig. 4, and after the work piece is suitably supported in bearings 5, the center is withdrawn and a ball 43 is placed in 25 the center opening in the work piece and the flat portion of the center brought up to a position to retain the ball in position and to prevent any substantial end-play or "floating" of the work piece. The screw mechanism for moving plunger 41 is operated from a hand wheel 30 or the like 44.

Head-stock 3 as particularly shown in Figs. 1 and 3 includes a housing or body portion 45 within which is suitably journaled a spindle 35 generically designated by numeral 46, and in the present instance formed in two telescoping sections 47, and 48, the spindle being driven from motor 13 by means of a belt 49, in the present instance of V-type, operating on a cone pulley 50, on motor 13, and driving the spindle by means of a cone pulley 51. By placing the belt on one or another of the various sized sheaves comprising the cones, various speeds may be obtained in the spindle 46, and motor 13 may be of a variable 40 speed type if desired to obtain still other variations of the speed in the spindle, although ordinarily the variation provided in the pulleys 45 should be sufficient.

To provide for promptly stopping the rotation 50 of the parts when desired pulley 51 serves also the purpose of a brakedrum, having an internal braking surface or bore 52 with which cooperates a brake shoe of suitable type 53 provided with friction material 54 and anchored on a stud or 55 the like 55 fixed with casing 45. The shoe may be expanded by operation of a hand lever or the like 56 extending forwardly into a convenient position, and actuating through a shaft 57 journaled in a bearing 58 on housing 45 a cam 59 60 acting on the shoe in any suitable or well known manner when the shaft is turned by actuation of the lever 56.

Shaft portion 47 is suitably journaled at one end in a bearing 60 fixed with housing 45, and at 65 its other end it is supported in the bore of portion 48 which is in the form of a sleeve journaled in a slidable bearing portion 61 carried in a guide or the like 62 projecting from housing 45. Portions 47 and 48 are slidably keyed together so that portion 48 may be axially moved with bearing 61 while the driving connection between the shaft portions is maintained. Portion 48 is prevented from moving axially in one direction in bearing portion 61 by a collar 63, 75

and in the other direction by a flange 64. Flange 64 also provides an abutment for a face plate 65 which may be threaded on the shaft portion in the manner common in machines of this type, 5 the face plate being provided with a bore for the reception of center 39 and with means for driving the work piece.

In the present instance the face plate is provided with a plurality of pins 66-66, spaced to 10 enter bolt holes or the like customarily found in work pieces of the type disclosed, the pins being fixed in the face plate as more particularly shown in Fig. 5, and provided with sleeves or bushings of yieldable material such for example as rubber 15 67-67. The bushings permit slight misalignment of the face plate and work piece without causing any binding of the working parts such as would affect the accuracy of the readings. To prevent axial movement of the work piece toward 20 the face plate bushings 67 are provided with flanges or the like 68, the piece when being tested being supported in the several bearings and floating between ball 43 and flanges 68.

Other types of drive are contemplated, and will 25 be required for different work pieces, but their form and character will depend upon the individual types of work piece upon which the machine is to operate. When a work piece is tested requiring a different form of drive from that 30 shown, the face plate 65 may be unscrewed and another fitting of suitable type substituted.

For axially moving portion 48, bearing 61 is 35 provided with a rack portion 69 traveling in the present instance in a slot 70 in guide 62, the rack being actuated by a sector 71 pivoted on a pin 72 or the like carried by a portion 73 of guide 62, the sector having a lever 74 fixed therewith and extended to a point within convenient reach of an operator. Swinging of the lever from side 40 to side accordingly causes in and out movement of bearings 61 and spindle portion 48 together with its attached face plate 65 or other fitting. A spring 75 disposed between lever 74 and an anchorage 76 on head stock 45 serves to urge the 45 lever yieldingly to the right as seen in Fig. 3, and prevent undesired retraction of spindle portion 48. The retracting feature of spindle portion 48 is useful in that it permits the ready removal of the center 39 after the work piece is 50 set up in bearings 5, and subsequently it permits the entering and withdrawal of pins 66 as new pieces are placed in the machine for testing.

Spindle portion 47 has a spiral or other suitable gear 77 fixed therewith which drives a gear 78 fixed on a shaft 79 extending diagonally upward to drive the indicating device 11 as more particularly shown in Fig. 6. A gear 80 engages gear 77 below shaft 47, the gear being fixed on a shaft 81 journaled in a bearing 82 suitably supported in housing 45, the shaft being prevented from moving axially by engagement of gear 80 and a collar 83 with the ends of bearing 82. A coupling element 84 of any suitable type connects shaft 81 with the operative element of a 60 flexible shaft 85 of suitable or well known type of which the outside casing only is shown, the shaft extending to above mentioned tachometer 15 in familiar manner. This type of drive permits convenient location of the instrument without the necessity for alignment of driving shafts, 70 and permits also removal of the instrument if desired for access to other parts of the apparatus. A removable bottom plate 86 permits access to the interior of housing 45 for assembly or inspection.

Continuing with the purely mechanical phases of the apparatus, each of bearings 5, includes a frame or body portion 87, Fig. 2, which as above described is fixed with guides 18 and 19 by suitable clamping means above described, the frame 5 acting to support the various elements carrying rolls 6, 7, and 8. Rolls 6 and 7 are journaled on pins or the like 88, each fixed in a bifurcated member 89 more particularly shown in Figs. 7 to 11 inclusive, the member comprising a flat bar 10 slotted for most of its length so as to provide lengthwise portions or legs 90 and 91 connected by a web 92, as clearly shown in Figs. 8 and 9, web 92 having forwardly projecting ears 93 and 94 carrying above mentioned pin 88, the pin 15 being retained in aligned bores in the ears by a pin 95 or the like, as shown in Fig. 7. Member 89 is slidable in a hub or clamp portion 96 fixed with frame portion 87 and may be clamped there-in to preserve a fixed relation to a work piece. 20

To provide for ready and accurate longitudinal adjustment of member 89, a screw 97 is provided extending lengthwise between members 90 and 91, the screw having a collar 98 fixed therewith as for example by means of a pin 99 engaging opposed transverse slots in the members, whereby longitudinal movement of the screw will cause similar movement of the member 89. The screw engages within the hub 96 in the present instance a pair of half-nuts 100 and 101 of a 30 cross section of a part of a circle and constituted to fit within a cylindrical bore 102 in hub 96 and against the sides of member 89, the half-nuts having inwardly extending threaded portions 103 and 104 extending into the space between members 90 and 91 and into engagement with the threads of screw 97. Half-nuts 100 and 101 are retained in the bore 102 by means of set screws or the like 105 and 106, threaded into the sides of hub 96 and entering suitable bores in the half-nuts. Rotation of the screw will accordingly cause longitudinal movement of member 89. Screw 97 may be rotated by means of a knob, grip, or the like 107, and a lock nut 108 may be provided engageable with the ends of members 45 90 and 91 to maintain any desired adjustment of the screw.

Hub portion 96 is slotted at 109, and provided with upstanding ears 110 and 111 through which extends a bolt or the like 112. The bolt in the 50 present instance is threaded in ear 111, and may be rotated by a lever 113 fixed therewith by suitable means such as a pin 114, tightening of the bolt compressing the hub 96 and clamping the half-nuts and members 90 and 91 securely together within the hub. 55

A duplicate of member 89 and its associated parts is located in an upwardly extending position in the lower middle portion of frame 87 for supporting roll 7 for carrying the weight of the 60 part of the work piece concerning the particular bearing element, and it is received in a boss or hub portion 115, Fig. 2 depending from the frame and slotted at 116 to permit compressing by a bolt 112 for clamping the member 89 in the manner outlined above.

As shown in Fig. 2, boss 115 supports member 89 carrying roll 7 in a position slightly inclined rearwardly toward the axis of the work piece, whereby the work piece is stably supported on 70 rolls 7 and 6 even when rolls 8 are removed from contact with it. As a result of this disposition of rolls 6 and 7, a downward thrust, as from a cutter, will have no component in the direction of roll 8, and the yielding characteristic of this 75

roll will accordingly have no undesirable effect on the support of the work piece for cutting.

The movements measured in the machine are very small, and it is accordingly important to preserve insofar as possible perfectly round faces on the rolls 6 and 7. To prevent damage of the rolls or the work pieces from impacts arising as the pieces are being placed in the machine, rests 117 are provided adjacent rolls 7 and the pieces 10 when first placed in the machine can be placed on these rests which will take the shock if the pieces are not placed in position as gently as they should be, and it is contemplated that the rests may be formed of a material which is sufficiently softer than that of the work pieces that any damage such as denting of the surface will take place on the rest, and not on the work piece. The piece after being placed on rests 117 may be moved into engagement with rolls 6 and 7, 20 and rolls 8 brought into position without danger of further damage. Rests 117 are provided with downwardly projecting bifurcated portions 118 which in the present instance are identical with portion 89 above described, adjustment of the 25 rests to the proper heights relative to rolls 7 being effected by a grip 119, and the adjustment maintained by a lock nut 120 in the manner described for members 89. Other expedients may be utilized for obtaining this adjustment, and it 30 is not essential to the invention that the adjusting means of the rolls 6 and 7 and rest 117 be identical, although it is preferable, for convenience in manufacture.

As above explained, roll 8 is carried by mechanism including a bracket 37 which is pivoted on a pin 121 extending in the present instance between webs 122 and 123 extending forwardly on frame 87, as particularly shown in Figs. 2 and 12, the bracket having a seating surface 124 contacting a complementary surface on the frame when the bracket is in its uppermost position, corresponding to the operative position of roll 8. Bracket 37 has an enlarged portion 125 at its upper end which is slotted to receive a shank portion 126 constituting part of above mentioned contact mechanism 10. A cap or clamp member 127 may be forced into clamping relation to shank 126 by means of screws 128—128 to rigidly maintain the shank in desired adjusted positions relative to bracket 37. A quick-acting clamp element is provided for maintaining surface 124 of bracket 37 seated against its complementary surface on frame 87 comprising in the present instance a bifurcated lever 129 including bracket 37 between its arms, and pivoted to the bracket by means of a pin 130 or the like, the arm having cam portions 131 and 132 exteriorly thereof engaging respectively cam portions 133 and 134 extending toward the arm 129 from webs 122 and 123, the complementary cam surfaces urging the bracket forcibly against its seating surface on the frame when the arm 129 is swung downwardly. A rod 135 may be run through suitable bores in the outer ends of adjacent arms 129 if desired so that several arms may be operated simultaneously, and one or more of the arms may be provided with set screws such as 136 which may be tightened to prevent displacement of the rods. To provide an adjustment to permit simultaneous taking up of the arms 129 the pins 130 are made with an eccentric middle or journal portion 137 as more particularly shown in Fig. 13a. Rotative adjustment of the pins will accordingly change the adjustment of the cams 131 and 132 independently of those of other bear-

ings connected by rod 135. Other expedients are contemplated for quickly clamping and unclamping brackets 37 as within the realm of the invention, the disclosed structure serving the purpose of allowing rapid opening and closing of the 5 bearings for quickly placing in position work pieces to be tested. As the bearing members are changed in position, the rod 135 slides freely through the bores in arms 129, and if any of the bearings are to be removed or replaced, the rod 10 is first removed from the arms, and after the desired change has been made the rod is replaced.

The construction of contact mechanism 10 is shown in Fig. 13. Shank 126 has a longitudinal guiding bore 138 in which is slidably guided a 15 plunger 139 which is preferably made as light as possible by boring out as shown at 140, the plunger carrying at its lower end a transverse web 141 having ears 142 and 143, Fig. 14, carrying roll 8 between them by means of a pin 144 on 20 which the roll is journaled. Pin 144 may be fixed in position by any suitable means such as a pin 145. Web 141 is spaced a small amount from the end of shank 126 to provide a clearance 146 to permit movement of plunger 139, but the clearance is preferably of an amount corresponding to a maximum desirable movement of the plunger so that deflections of the work piece which cause movement of the roll 8 and its connected parts will be positively limited by the amount of the 25 clearance.

The outward movement of the plunger is limited by a pin 147 fixed transversely of plunger 139 and received in a slot 148 which is of sufficient extent to permit the desired movement, the 35 slot preferably exerting a guiding action to maintain roll 8 in a plane substantially parallel to any diameter of the journal being tested. Pin 147 may be prevented from moving axially in plunger 139 by any suitable means such for example as a set screw 149.

Movement of plunger 139 caused by deflections of the work piece is resisted by a compression spring 150 also guided in bore 138, the spring being urged into contact with the end of the 45 plunger by means of a threaded rod 151 engaged in a threaded bushing 152 fixed for example by a set screw 153 in a hub or barrel portion 154 of a cover member 155 which is fixed on a housing 156 by suitable means such as screws 157. 50 Rotation of the rod will accordingly change the degree of compression of the spring, and consequently the amount of pressure necessary to produce movement of plunger 139, and such rotation may be effected by means of above mentioned grip or cap member 12. The cap and barrel 154 are preferably graduated as above mentioned and as shown in Fig. 2 so that any desired pressure may be immediately developed in spring 150. 55 To compensate for variations in springs 150 as 60 manufactured, and for providing various ranges of pressure in the same structure, spacers such as 158 are preferably inserted in bore 138 between spring 150 and rod 151, the spacers furnishing a means of changing the compression in the 65 spring for any given setting of the cap 12.

Movement of plunger 139 is caused to control an electric circuit, as briefly outlined above, and for this purpose pin 147 has threaded thereto, or otherwise fixed therewith an actuating rod 70 159 extending upwardly through a bore 160 in shank 126 and having a pointed end portion 161 engaging one or another of suitable sockets 161a and 161b, Figs. 16 and 17, disposed on opposite sides of sockets 163a, mentioned below, in a con- 75

tact lever element generically designated by numeral 162 composed in the present instance of two sections 163 and 164 riveted or otherwise fixed together, but insulated from each other by 5 suitable insulating material 165. Section 163 is provided with suitable sockets 163a for the reception of the pointed ends of pivot screws 166 and 167, Fig. 15, about which lever 162 pivots in response to longitudinal movement of rod 159. 10 Lever 162 is urged in either an upward or a downward direction by a spring 168 which is fixed with section 164 and electrically connected therewith, the spring being readily bent slightly to give the required action. The spring maintains 15 mechanical contact between section 163 and rod 159, and owing to the construction employed the lever arm between the fulcrum represented by screws 166 and 167 and the point of contact of rod 159 may be made very short. Very slight movements of rod 159 are therefore multiplied at the free end of lever 162 to appreciable amounts.

The reason for providing two sockets 163a and 163b is to make possible the use of the contacting mechanism with various types of indicating mechanism described below, certain of which operates to better advantage with the contacts normally closed and opening upon deflection of the work piece, and certain of which requires the contacts to be normally open and to close upon 25 deflection of the work piece. With rod 159 in socket 163a, as shown in Fig. 17, and spring 168 acting downwardly, the first situation is established, and with the rod in socket 163b as shown in Fig. 16, and the spring acting upwardly, the second situation is established. The flexibility of rod 159 and the size of bore 160 are such as to permit the slight misalignment of rod 159 which occurs when it is changed from one socket to the other, the distance between the two being very 30 slight, and shown much exaggerated in the drawings.

Other bearing constructions are contemplated for the lever arm, those shown being chosen as 45 illustrative merely. The outer ends of screws 166 and 167 are in the present instance arranged to be covered by the edges of cover plates 169 and 170, which are arranged to close in the open sides of housing 156, being held in place by screws or the like such as 171.

50 Section 164 is provided at its free end with a contact point 172 which is arranged to cooperate with a complementary contact point 173 in the present instance fixed on the end of an adjusting screw 174 threaded in a bushing 175 insulated from housing 156 in any suitable manner as by an insulating bushing 176, a grip 177 permitting adjustment of the screw, and a lock nut 178 acting against the bushing 175 to maintain any desired adjustment. Electrical connection to the 55 bushing and accordingly to contact point 173 is made in the present instance through a binding post of conventional or suitable character generally designated by numeral 179 also insulated from housing 156 by an appropriate bushing 180 and washers 181 and 182. Electrical connection may be made to contact point 172 through spring 168 which is connected at its end remote from section 164 with a conventional or suitable binding post 183 which is also insulated from housing 156 by a bushing 184 and washers 185 and 186. Thus if the contacts are to be used as part of a two-wire circuit, connections can be had to the two points independently of the frame of the machine, whereas if a one-wire circuit is 70 to be used it is only necessary to connect one

or the other of the binding posts 179 or 183 with the frame, or omit the insulating washers from one of the posts. It is contemplated that the contacting mechanism will be used with different types of indicating apparatus requiring both types 5 of circuits, and it is desirable to be able to use the same contactor structure with either type. For use with a one-wire circuit lever 162 might be conveniently made in one piece, or insulation 10 165 might be omitted, and other such variations 15 will suggest themselves to those skilled in the art, and are contemplated as within the scope of the invention.

For convenience in moving shank 126 in bracket 37 to accommodate journals of different 15 sizes, a screw 187 is provided journaled in a bearing portion 188 extended from shank 126, the screw being prevented from moving axially relatively to the shank by means of a collar 189 received between bearing 188 and a portion of cover member 155. Screw 187 is engaged in a threaded bore in bracket 37 adjacent the slot through which passes shank 126, whereby rotation of the screw will cause movement of the shank at such times as clamp portion 127 is out of clamping 25 engagement therewith, and a lock nut 190 on the screw may be tightened against bracket 37 to maintain various adjustments of the parts. For rotating the screw an extension 191 projects above cover member 155 for the reception of 30 a removable key, crank, or the like 192 which fits thereon and engages a transverse pin 193 fixed in the extension.

From the above it will be understood that with 35 roll 8 in contact with a work piece supported on rolls 6 and 7 any deformation of the piece will cause movement of roll 8 and plunger 139, the movement being multiplied by lever 162 and making or breaking any circuit that may exist through contacts 172 and 173. Any desired 40 amount of resistance may be offered to such movement by spring 150, and the amount read directly from the graduations on cap 12 and barrel 154. Adjustments may be made also at the contact points by means of screw 174, and the 45 position of the roll 8 may be adjusted by means of screw 187. The maximum possible deformation of the piece is determined by the clearance 146 which is preferably small enough to prevent any dangerous distortion, but in practice the 50 spring 150 would normally be tightened to a point where it would prevent movement of the plunger through the whole of the clearance space. From the spring pressure necessary to do this the magnitude of the unbalanced forces in 55 the work piece can be determined as outlined above, and from the position of the piece when its deflection causes movement of the contacts, the angular location of the unbalanced weight can be determined with one or another of the 60 following indicating devices.

The device 11 shown in position on the machine in Fig. 1 is shown in detail in Figs. 18 and 19 and comprises a stroboscopic device in which a disk 194 is driven in synchronism with the 65 work piece 4, and flashes of light from a discharge tube or the like 195 produced upon opening of the contacts 172 and 173 at one of the bearings 5 are observed through an opening 196 in the disk. Since the disk is synchronized with 70 the work piece, as also are the breaks in the circuit caused by the deflections of the piece, the opening appears to remain stationary, and the position which it takes up gives an index of the location of the heavy spot in the work piece. 75

This apparent position may be noted for future reference against a suitably graduated scale 197.

Disk 194 is driven from above mentioned shaft 19 through a lag compensating mechanism generally denoted by numeral 198, Fig. 6, the disk being fixed with a shaft 199 carried in a bearing 200 supported from a portion of a housing 201 arranged to enclose the indicating mechanism. Shaft 199 is maintained against axial movement by a head portion 202 to which disk 194 is attached by suitable means such for example as rivets 203, and by a collar 204, the head and collar engaging opposite ends of the bearing. Housing 201 provides an annular rim 205 which projects inwardly to within a short distance of the periphery of disk 194, and carries above mentioned scale 197. Rim 205 carries behind disk 194 a translucent member 206 which may be held in place by any suitable means such for example as a flange 207 against which the member is held by a spring wire ring 208. Member 206 will distribute the light from tube 195 so as to uniformly illuminate the opening 196 and make reading thereof easier. A ring 209 fixed with housing 201 by suitable means such as screws 210 may be utilized to hold a glass or other transparent closure 211 which may be spaced from scale 197 and disk 194 by a gasket or other spacing means 212, thus excluding dirt, and protecting the operator from any danger due to the rapidly rotating disk.

Tube 195 is excited from a coil 213 having primary and secondary windings 214 and 215, Fig. 20, of suitable or well known type, and suitable connections extend from the secondary to the tube, for example, one terminal of secondary 215 is connected to one terminal 216 of the tube by means of a flexible lead 217, the lead containing sufficient slack to permit removal of coil 213 from housing 201 by removing screws 218, and being connected to the coil through a quick-detachable plug 219 of suitable or well known type. The other secondary terminal is preferably connected with the coil housing so that the secondary circuit may be completed through the metallic parts of the machine from the other terminal 220 of the discharge tube 195. Current reaches the primary winding of the coil 213 through a flexible cable 221 containing conductors 222 and 223, Fig. 6, the circuit arrangement being more particularly shown in the wiring diagram Fig. 20.

The circuit illustrated shows a two wire system, and the apparatus has been arranged with this type of circuit in view, but it is to be understood that a one wire system could be used in lieu of that shown with some consequent simplification of the apparatus, one of the wires being replaced by the metal parts of the machine. Since this practice is well understood in the electrical art, and since the adaptations necessary could readily be performed by one skilled in the art, the disclosure will be confined to the two wire system, but it is to be understood that this is not to be taken as limiting the invention to the details of the circuits disclosed, or in fact in any manner except as defined in the claims.

As shown in Fig. 20, current may flow from generator 14 through lead 223 for example to the primary coil 214 constituting part of coil 213, leaving the primary through lead 222, the current then flowing through a lead 224 extending the length of the base 1 of the machine. From this lead the current flows through one or another of a plurality of leads 225-225 according to which of them is connected with lead 224 through switches 226-226, the current traversing above

described spring 168, lever portion 164, contacts 172 and 173, screw 174, and returning through one of leads 227-227, a switch 226 and a lead 228 to generator 14. So long as a steady current flows in the above outlined circuit there will be no voltage induced in the secondary 215 of coil 213, but if the circuit is broken through separating of contacts 172 and 173 caused by deflections of the work piece or by other influences, a momentary high voltage will be induced in the secondary in familiar manner and a momentary excitation of tube 195 will take place. This will have a definite time relation to the deflection of the work piece, and will serve to momentarily illuminate the opening 196 in disk 194, and since the disk rotates in definite relation to the work piece, and is illuminated once in each revolution thereof, and always at the same point in its revolution, the opening will appear stationary at some definite point in its travel indicative of the position of the heavy spot in the work piece. The apparent location of the opening may be noted, after which the machine may be quickly stopped by means of brake lever 56, and the work piece rotated by hand or otherwise to the position where the opening 196 is returned to the position observed when it was rotating, when the work piece will be in the position which it occupied at the instant the deflection took place.

Any convenient expedients may be used in providing the circuits outlined, and variations or additions known to those skilled in the art may be made, such for example as a condenser 229 connected across primary 214. In practice the leads are preferably carried in protecting conduits 35 where possible, as more particularly shown in Fig. 1, leads 222 and 223 being housed in flexible conduit 221, and leads 224 and 228 being extended along the front of the machine in a conduit 230, the conduit being provided with outlets 231-231 40 of suitable or standard type by which connection may be established with the leads within. Leads 225 and 227 are contained in flexible cables 232-232 which are provided at their ends with terminal plugs 233-233 for ready connection 45 with the outlets 231-231, and switches 226-226 are interposed in the leads between the plugs and the upper termini of the leads as more particularly shown in Fig. 12. This arrangement permits the locating of bearings 5 wherever desired, after 50 a bearing is placed, its cable 232 being plugged into the nearest or most convenient of the outlets 231.

To assist in preserving throughout the duration of the test the data determined at each reading means is provided in the form of dials 234-234, each provided with manually movable hands or other indexes 235 and 236 traveling over appropriate scales laid out on the dials. One of these may conveniently read angles, and another speeds of rotation, although other data may equally well be represented on the dials if desired. When an observation is made at a given bearing the hands may be moved to the values noted, and observations made at as many of the 65 remaining bearings as desired before the machine is stopped, after which the work piece may be immediately placed in the position at which deflection took place at any desired bearing by noting the setting on its dial 234. The speed of 70 rotation at which this deflection took place may also be read off the dial, and the force necessary to substantially balance the deflecting tendency may be read from the position of cap 12. The piece may be marked at each journal with 75

this data, including the location of the excess weight, the necessary calculations made and the appropriate amount of material removed at each location, whereupon the piece will be in substantially perfect balance as outlined above.

It is understood that in apparatus of this nature there is a certain amount of lag in the electrical or other portions of the device, and to avoid the necessity for including this in the calculations, above mentioned lag compensator 198 is provided. This device is shown in Fig. 6 and comprises a speed responsive device mounted on above mentioned shaft 79. The shaft is journaled in a bearing 237 fixed with a portion of housing 45, a closure 238 carrying a second bearing 239, the two bearings engaging the end portions of gear 78 and preventing axial displacement of the shaft. Shaft 79 has fixed therewith upwardly of bearing 237 a yoke member 240, the yoke being threaded on the shaft in the present instance and provided with a lock nut 241 to maintain its position. Yoke 240 has pivoted thereto by means of suitable pins 242-242 arms 243-243 carrying weights or "fly-balls" 244-244 which tend to swing out from the shaft as rotation takes place. The swinging movement is resisted by links 245-245 pivoted adjacent the weights by means of pins or the like 246-246, the links being pivoted at their other ends to a sleeve 247 slidably keyed to shaft 79, by means of a feather key or the like 248, pins 249-249 serving to connect links 245 with the sleeve. Shaft 79 terminates within sleeve 247, and above mentioned shaft 199 extends downwardly from indicator 11 into the sleeve and is driven therefrom by means of a pin 250 fixed in the shaft transversely thereof and engaged in a pair of opposed slots 251, one of which is shown in Fig. 19. Axial movement of the sleeve is produced by outward movement of weights 244, and this is caused to effect the desired compensation by shaping slots 251 to cause relative rotation of shafts 199 and 79 of an extent determined by the amount of lag observed at various speeds in any convenient manner, as for example when a work piece is tested having a heavy spot of known location. Axial movement of sleeve 247 is resisted by a spring 252 disposed about shaft 79 and compressed by an adjusting nut 253 threaded on the shaft, and by means of which adjustments of the spring force may be accomplished. Through the action of this device the position observed on the indicator 11 is always the true position of the work piece obtaining at the instant the deflection takes place, and not a value which must be corrected to determine the actual position. The compensator may be reached for assembly, adjustment or the like through an opening covered by a closure 254.

In addition to the means just described for indicating the angular position of unbalanced weight in a work piece, other indicating means is contemplated and may be used within the scope of the invention. In Figs. 21 to 24 inclusive a system is shown which among other advantages avoids the use of high voltage. Referring first to Fig. 24, the system includes a plurality of incandescent lamps 255-255, preferably arranged in a ring-shaped group and connected in series with each other by connections 256-256. Current is supplied from generator 14 through a lead 257 at one or more points 258, and divides and flows around the group from each point in two directions as indicated by the arrows, and leaves the group at a plurality of points 259, returning to

the generator through a lead 260. The group of lamps is accordingly divided into a plurality of series, and the number of series and the number of lamps in each may be chosen in accordance with the voltage of the generator and the voltage of the lamps it is desired to use. In the working embodiment described below, for example, it is contemplated to use one lamp for each three degrees in the circle, or 120 lamps. These are divided into six series of 20 lamps each, there being three taps corresponding to taps 258 and three corresponding to 259 on the complete ring. With a generator giving 110 volts, this would result in an effective voltage on each lamp of five and one-half volts.

The lamps are arranged to be successively momentarily short circuited whereby, owing to the time lag between beginning of current flow and attainment of normal brilliancy present in incandescent lamps, they will not reach their full brilliancy, but will burn somewhat more dimly than they would if operating on a steady current. The short circuiting means includes a commutator 261, each of the segments 262 of which is connected with one of the connectors 256 by means of a lead 263. Connecting of any two adjacent segments will thus short circuit the particular lamp which happens to be between the conductors 263 connected with the adjacent segments. The connecting may be done by a rotating member 264 driven in synchronism with the work piece and carrying a pair of spaced brushes 265 and 266, insulated from each other, and from which connections are taken respectively to above mentioned leads 224 and 228 by any suitable means.

Assuming one of the switches 226 closed, the lamps will be short circuited through the above described connections once during each revolution of the member 264, except at such times as contacts 172 and 173 are opened by deflection of the work piece or otherwise. Since such opening of the contacts will take place once during each revolution, and always at the same point in each revolution, the short circuit will be constantly broken at the time member 264 is in contact with a certain pair or group of segments in commutator 261, with the result that the particular lamp or lamps controlled by those segments will not be short circuited, but will receive a steady uninterrupted supply of current at full voltage. The lag effect will not be present in this lamp, and it will burn with its full brilliancy, standing out from among the dimmer lamps, and marking the location of the work piece at the instant deflection takes place.

It is to be noted that the brilliancy time lag effect in incandescent lamps generally disqualifies them from uses relating to apparatus of the character of this invention, but in this device this lag is taken advantage of in the working of the device, and it is contemplated that the old style carbon filament lamps would be satisfactory in the present indicator, and possibly superior to the tungsten or other more advanced types.

In the working embodiment shown in Figs. 21 to 23, the device is enclosed in a housing 267 which is supported in the manner of housing 201 from the head-stock, the mechanism being driven from the lag compensator sleeve 247 in the same manner as indicator 11, a shaft 268 carried in a bearing 269 extending to the sleeve and being driven therewith by a pin 270. Shaft 268 extends forwardly in housing 267 and has fixed therewith the rotating member 264 cooper-

ating with commutator 261, the lamps 255 being supported in a socket carrying member 271, and the readings taken against a scale 272 the graduations of which approach as nearly as practicable to the lamps 255, as particularly shown in Fig. 21.

Commutator 261 comprises in the present instance a plate 273 of insulating material about which a clamping ring 274 clamps a series of segments 275—275, the segments having dovetailed projections 276 which are gripped between the plate and the ring when the latter is forced toward the plate by suitable means such as screws 277, certain of the screws 278 passing through the plate into housing 45 to maintain the plate in position. Segments 275 may be slightly spaced from each other or separated by insulation 279 in the manner well understood in commutator construction. Slip rings 280 and 281 are mounted on the face of disk 273, being held in place by screws or the like such as 282 and 283 respectively, suitably spaced about the length of the rings.

Member 264 in the present instance is formed of insulating material, and is slotted at 284 and provided with a clamping screw or the like 285 by means of which the member can be rigidly secured on the shaft in any desired relation thereto. The member carries above mentioned brushes 265 and 266, the brushes being disposed in the present instance in substantially radial slots such as 286 formed in the end of the member and spaced the desired distance from each other, preferably the center-to-center distance of the segments 275. Brush 265 is fixed on a flat spring 287 which maintains the brush in its slot and yieldingly presses it against the inner surface of the commutator 261, the spring also being fixed with member 264 by screws or the like 288, and extending toward shaft 268 and having a portion pressing on a brush 289 slideable in a suitable bore in member 264 substantially parallel to shaft 268, and pressing the brush into contact with slip ring 280. In a similar manner a spring 290, also fixed with member 264 presses brush 266 against commutator 261 and connects with and presses a brush 291 against slip ring 281. Connection may accordingly be established with rotating brushes 265 and 266 by merely connecting with slip rings 280 and 281.

Socket carrying member 271 comprises an annulus of suitable insulating material seated in housing 267 against a shoulder 292, the annulus having a forwardly projecting rim 293 against which dial 272 is secured for example by screws such as 294. Socket member 271 is provided adjacent its periphery with a series of bores 295—295, Fig. 23 for the lamps 255, each bore being provided with a threaded bushing 296 after the manner of a conventional lamp socket, and each bushing has a finger 297 fixed therewith and extending into a position behind and approximately axially of the bore of its next adjacent bushing. Each bushing therefore constitutes an individual lamp socket with the help of the finger fixed with the next adjacent bushing, and when the bushings are filled with lamps as shown in Fig. 23, the lamps are connected in series without resort to other connections. This arrangement is of course for use with lamps of the screw base type and constitutes a means for holding the lamps and establishing the desired connections in a simple and convenient manner. Other expedients are contemplated as equivalent

and if it is desired to use other types of lamps adaptations therefor may be made by those skilled in the art within the province of the invention.

In the illustrated structure wherever it is desired to establish connections with the series between the lamps as shown in the diagram it is conveniently done by connecting a conductor with one of the fingers 297 as by soldering or the like. Thus conductors 298—298 are so connected with each of the fingers 297 and each conductor is also connected with one of the segments 275, adjacent fingers 297 being connected with adjacent segments preferably by soldering or the like so that the act of connecting adjacent segments will short circuit one of the lamps 255 for the purpose above explained.

Current is supplied to the lamps by means of leads 257 and 260, which are enclosed in a flexible cable 299, similar to above described cable 221, the leads coming directly from generator 14 through appropriate conduits as shown in Figs. 22, and 1. In order to avoid the necessity for an excessively high voltage in generator 14, the group of lamps is divided in the present instance into a plurality of series, leads 257 and 260 being connected respectively to conductors 300 and 301 disposed around the interior of the housing adjacent to fingers 297, and constituting feeders for the series of lamps. Feeder 300 has a plurality of branches 302, in the present instance three, connected as above noted with fingers 297 at equal angular intervals about the group, while feeder 301 has similar branches 303 also connected with fingers 297 at points midway between branches 302. This arrangement divides the lamps into six independent series, and gives convenient values for the voltages of the lamps and generator. Obviously other numbers of series could be employed if desired by changing the number of branches, and any such variation is considered to be within the scope of the invention.

Leads 224 and 228 in this embodiment are extended from conduit 230 through conduit 299 and connected respectively with slip rings 280 and 281. The action of contact points 172 and 173 accordingly determines when the electrical connection between brushes 265 and 266 will be interrupted, and the position of the member 264 at the time this connection is broken will determine which of the lamps 255 will receive a continuous supply of current and therefore burn at full brilliancy.

Shaft 268 carries a pointer or the like 304 which is utilized after the machine is stopped to permit returning the work piece to the positions observed by means of the lamps, and if desired a manually movable index 305 may be provided to assist in the observation of the angle indicated by the lamps that are bright. The housing may be closed by a glass or other transparent member 306 held in place by a ring 307 secured on the housing by suitable means such as screws 308, the glass seating in the present instance against a liner 309 slideable in housing 267 and bearing against socket member 271. This furnishes a convenient means for holding the socket member in place while permitting the use of a large portion of the area thereof adjacent the periphery. Index 305 if used may be fixed with a shaft 310 journaled in a bushing or the like 311 carried by the member 306, the shaft being provided with a grip or knob 312 by means of which the index may be controlled. Index 305 may be omitted if desired, but in the event that several lamps are bright as might be the case unavoidably under certain conditions, it

would facilitate determining the mid-point of the bright portion of the group, which would be the desired reading. Such an index might be applied to the indicator disclosed in Figs. 18 and 19 within 5 the scope of the invention.

Other means are contemplated for indicating the angular location of the work piece at the instant of deflection, and an illustrative example of another type of indicator is shown in Figs. 25, 10 26, 27, and 28. In this arrangement a pointer is fixed at the instant of deflection of the work piece with a shaft portion which is rotating in synchronism with the work piece, the shaft portion being then stopped, the relation of the pointer there- 15 with read, and the shaft reengaged with the mechanism for another reading.

As seen in Fig. 25, a shaft portion 313 is driven from sleeve 247 of lag compensator 198, the shaft being provided with a pin 314 engaged in a slot 20 315 shaped to provide the desired correction for lag as explained in connection with the above described indicators, shaft 313 driving, through a jaw-clutch generically designated by numeral 316 a shaft portion 317, the shaft portion having an 25 internal tapered seat 318 within which a complementary tapered element or bell 319 may be seated by means of an impulse from an electromagnet 320, the bell element carrying a pointer or index 321 indicating against a scale 322 rotating 30 with portion 317.

Shaft portion 313 is carried in a suitable bearing 323 suitably retained in a partition or the like 324 constituting part of a head-stock similar to head-stock 3, by suitable means such as a ring 325 held by screws or other suitable means 326; the shaft being also maintained in alignment by its sliding engagement in sleeve 247. Shaft 313 terminates at its left end as seen in Fig. 25 in a head 327 forming part of the clutch 316. Shaft portion 317 has a reduced pilot portion 328 extending into a suitable bore in portion 313, through which portion 317 receives support from bearing 323, the pilot portion serving to further assist in aligning portion 313. A clutch member 329 is slidably keyed on portion 317 and forced 40 into yielding engagement with head 327 by means of a spring 330, and head 327 is provided with a groove or channel 331 Fig. 26 of a wide V shaped cross section, the channel being transverse to the axis of the clutch member but displaced from the 45 axis as shown. Channel 331 is engaged by a rib 332 of complementary cross section and position on clutch member 329, through which the clutch member and its connected parts are driven from 50 shaft 313.

Owing to the radial displacement from the axis of the clutch member and shaft, the rib and groove will fail to register in any but one position, and as a result, shaft portion 317 will always be 55 engaged in the same angular relation with shaft portion 313 when the clutch is engaged. If shaft portion 313 is rapidly rotating when the clutch is allowed to engage there will be no shock, but rib 332 will fail to enter groove 331 under the urge of spring 330, sliding on the surface 333 of the head 327 until clutch member 329 has attained substantially the same speed as the head 327, when the rib will engage the groove and a positive connection will be established. Clutch member 329 is provided with an annular groove 334 60 engaged by a pin or the like 335 carried by an arm 336 fixed on a shaft 337 journaled in a bearing 338 carried by a wall of a housing 339 forming part of the above mentioned head-stock, the 65 shaft extending outside of the housing and having 70 75

fixed therewith a lever 340 provided with a pad or grip 341 for manual manipulation. Depressing of lever 340 will stop shaft portion 317 and permit reading of the dial 322, and releasing it will permit reengagement of clutch 316 preparatory to another reading.

Shaft portion 317 is provided with a keyway 342, and is enlarged at 343, providing a shoulder 344 against which spring 330 bears. Enlarged portion 343 has a bore 345 in which is disposed a sleeve portion 346 carrying above mentioned seat 318. The sleeve may be threaded into the bore at 347 or otherwise suitably fixed therein, and provided with a head or flange 348 serving to retain a suitable bearing 349 preferably of an anti-friction type in position on the portion 343. Bearing 349 is carried in a partition 350, and retained therein by means of a plate 351 held by screws or the like 352. Bearing 349 serves to support shaft portion 343 and dial 322, and with 20 bearing 323 maintains the parts in position against the thrust of spring 330. This construction is satisfactory particularly since the spring 330 is fairly light, but other well known or suitable arrangements might be adopted within the scope 25 of the invention in which the spring thrust is not transmitted to the bearing supporting the mechanism. Dial 322 is fixed with head 348 by suitable means such as screws 353.

Bell member 319 has a neck portion 354 journaled on a pin or rod 355 projecting into sleeve 346, the neck portion carrying an armature member 356 disposed within the field of magnet 320, and pointer 321 is preferably fixed with the armature and extends beyond the periphery of dial 35 322 in the present instance so as to contact, at such times as bell 319 is disengaged from seat 318, a pin or the like 357 fixed with a portion of partition 350. Pointer 321 is preferably provided with an indicating point 358 spaced from pin 357 40 toward the axis of dial 322 for convenience in reading against dial 322, and pin 357 may be provided if desired with an indicating point 359.

After engagement of bell 319 with seat 318, pointer 321 will occupy some definite relation to 45 dial 322, and after these indications have been read and noted for all the journals on the work piece, the piece may be stopped, and rotated by hand or otherwise with clutch 316 engaged until the various values are indicated against point 50 359 when the piece will be known to be in the position in which deflection took place at the particular journal for which the particular value was noted.

Magnet 320 includes a core 360 on which is disposed a coil 361, the coil being connected with other portions of the operating circuit by leads 362 and 363 enclosed in a flexible sheath 364. Core 360 is secured in a suitable bore in a bracket 365 secured to portion 339 by screws or the like 60 65 366, the core having a nut 367 thereon for clamping it in the bracket. Pin 355 is slidable in a suitable bore axially of core 360 as shown and has an enlargement 368 arranged to encounter armature 356 when the pin is moved to the right as shown in Fig. 25, for the purpose of dislodging bell 319 from seat 318 after a reading has been secured. A knob or the like 369 is fixed with rod 355 for convenient manipulation thereof.

For use with this type of indicator the contact 70 elements 172 and 173 are arranged in the "Open circuit" position as above explained and shown in Fig. 16, and the connections are as indicated in the wiring diagram Fig. 28. Starting with generator 14 the circuit leads for example 75

through lead 362 to coil 361, through the coil and lead 363 enclosed in abovementioned conduit 230, through one or another of switches 226 and leads 225 to one of the springs 168. The 5 circuit is completed at the instant contacts 172 and 173 are closed, through one of screws 174, leads 227, switches 226 and a lead 370, also in conduit 230, to generator 14. The momentary flow of current causes magnet 320 to attract 10 armature 356, and stick bell 319 in tapered seat 318, thereby locking pointer 321 in the relation with dial 322 corresponding to the position of the work piece at the instant of deflection, pointer 321 moving to the left out of engagement with 15 pin 357 upon movement of armature 356.

Whatever lag is present in the mechanism is compensated by retarding dial 322 relatively to the work piece by means of device 198 above described, slot 315 being contoured as necessary to 20 suit the characteristics of the mechanism as determined by experiment with a weighted work piece or otherwise.

In addition to providing means in the machine for determining the location and amount of unbalanced weight in a work piece means is provided for correcting the unbalance by removing material from the work piece while it is still in the machine, it being then possible to re-test the 25 piece after the correction has been made. The 30 particular arrangement of the supports 89 makes this readily possible, the work piece being firmly supported at closely spaced points.

Various apparatus might be utilized for this purpose, but in the present instance a milling 35 head of suitable or well known type is used which may carry a suitable tool such as a milling cutter, drill, grinding wheel or the like, and which may be moved into position to operate on various desired parts of the work piece. As shown particularly in Fig. 29, the mechanism used in the present instance includes a channel member 371 fixed with the rear wall of base 1 by bolts or the like 372, the member being provided with suitable guides 373 and 374 on which is slidably mounted 40 a column or support member 375, extending upwardly and provided with spaced guides 376 and 377 against which is slidably mounted a carriage 378. Carriage 378 has an arm 379 projecting forwardly over the machine and having spaced 45 guides 380 and 381 on which is slidably mounted a carrier 382 which carries a spindle carrying head 383 in the present instance angularly adjustable about an axis transverse to that of the work piece. Head 383 carries a tool spindle 384 on which may be fixed a cutter of a type to suit 50 the work in hand. Since the particular construction of the milling machine portion of the apparatus is not a part of the present invention, and since the details of such apparatus are generally well known, the gearing, power trains, clamping mechanism, etc. are not shown in detail, and do not need to be completely described for a full understanding of the invention.

Sufficient to say, gibs 385 and 386 are provided 55 for securing proper running fits between guides 373 and 374 and the adjacent portions of column 375, a screw 387 or the like extends through the column between the guides and may be engaged by suitable mechanism not shown for sliding the 60 column along the member 371, and a screw 388 is arranged for raising and lowering carriage 378. A shaft 389 projects from the forward end of arm 379 and is squared for the reception of a crank or the like of familiar type, not shown, the shaft 65 having suitable connections for rotating and the

carriage may be clamped in adjusted position by means of bolts 390—390. Carriage 378 carries a motor or other power source 391, a transmission means 392, a rate changer 393 and certain other apparatus which will be described presently. Power is transmitted to head 383 by means of a shaft 394. 5

Carrier 382 may be clamped in adjusted position by suitable mechanism actuated by handles 395—395, and head 383 may be clamped by means of a handle 396. A shaft 397 projects from the forward portion of arm 379 and is squared for the reception of a crank or the like of familiar type, not shown, there being suitable connections within the arm and column for sliding the column by 15 means of screw 387, and a shaft 398 of similar character projects from the arm and has suitable connections for sliding carrier 382 along arm 379. Spindle 384 may be fed up or down through suitable mechanism of well known type by means of 20 a hand wheel 399. It may accordingly be brought to bear upon any desired portion of a work piece and at any angle required by the previously determined location of the unbalanced weight.

For convenience in accurately determining the 25 depth which a cutter has reached a dial indicator is provided as follows: Spindle 384 is carried in a long quill 399a extending upwardly from the head 383, and a dial indicator of suitable or well known type 399b, Fig. 29a, is adjustably fixed 30 therewith by means of an extension 399c clamped therearound by suitable means such as a thumb-screw 399d. The indicator has in the present instance a hand 399e, a counter 399f, and a stem 399g, the latter positioned to contact a pad 399h 35 on head 383 through which the indicator mechanism is actuated by movement of the quill 399a. The cutter or drill may accordingly be set in contact with the work, after which extension 399c may be clamped in a convenient position on quill 399a, the progress of the cutter into the work 40 then being accurately indicated on the indicator 399b. Other means might be utilized for supporting the indicator in proper relation to the spindle, and any such are contemplated within 45 the scope of the annexed claims.

For accurately determining the actual amount of material removed from a work piece weighing means is provided. A suitable cutter 400, with spindle 384, is enclosed in a box or chamber 401 which is connected by means of a flexible or other suitable conduit 402 with the intake 403 of a suction fan or the like 404 driven in the present instance by a shaft 405 from a suitable portion of transmission 392. Substantially all the material removed in the form of chips by cutter 400 is picked up by the current of air running through the box 401 and conduit 402, and discharged from the fan through a pipe 406 into an extractor of centrifugal or other suitable type 407, from which it drops onto a pan 408 suspended by chains or the like 409 from an arm 410 of a scale mechanism of suitable type enclosed in a housing 411, the weight being indicated on a dial 412. Since movement of the chips through the system is very rapid, the chips accumulate on pan 408 substantially as fast as formed, and the operator, knowing from previous calculations the weight of chips to be removed from any particular location, may continue cutting until the dial 412 indicates 70 the required amount, when the operation is complete for that location. The milling head may then be moved by means of the various controls and correction made at the remaining points of unbalance, after which the piece may be again 75

tested if desired to check the accuracy of the correction.

For some purposes it may be desirable to eliminate the step of calculating the moment of the unbalance as determined from the various indications of the machine. The mechanism shown in Figs. 30 to 33 inclusive accomplishes this. In this arrangement a dial 413 similar to above described dial 194 is driven through a lag compensating mechanism generically designated by numeral 414, similar to mechanism 198 above described, from spindle 41, but mechanism 414, in addition to its compensating function, actuates a dial 415, in the present instance annular in form and rotatively mounted adjacent a complementary dial 416, the movement of the dial being proportional to the logarithms of the various speeds of the mechanism, and the dials being provided with suitable scales upon which the desired values are directly indicated.

The parts are mounted in a special head-stock 417 of suitable form, portions of which are shown in Fig. 30, spindle 41 driving, through suitable spiral or other gears 418 and 419 a vertical shaft 420 journaled in suitable bearings 421 and 422 and extending upwardly into a sleeve 423 constituting part of lag compensating mechanism 414 which it drives through a pin 424 engaging a cam slot 425 formed in the sleeve. Sliding of the sleeve on shaft 420, through this connection causes relative angular displacement between the shaft and sleeve. Sleeve 423 extends beyond shaft 420 and embraces a shaft 426, being slidably keyed therewith by means of a key or the like 427, whereby shaft 426 is driven in the same relation to shaft 420 as is sleeve 423. Sleeve 423 has collars 428 and 429 for transmitting reciprocating movements thereof to dial 415. Shaft 426 continues upwardly and is carried in a bearing 430 of suitable type fixed with head-stock 417, the shaft having fixed therewith, as for example by means of nuts 431—431 a yoke 432 carrying depending arms 433—433 pivoted thereto by suitable pins 434—434. The arms carry weights 435—435 which in the present instance are formed as particularly seen in Fig. 31 of a plurality of washers held together by a bolt or the like 436. The weights are thus readily adjustable by adding or removing washers.

Arms 433 are connected with sleeve 423 by means of links 437—437, the links being pivoted to the arms by suitable pins or the like 438—438, and to the sleeve by pins 437a—437a, and when the structure is rotating centrifugal force acting on weights 435 tends to cause them to swing outwardly and raise sleeve 423 in the manner common in apparatus of this nature. This movement of the sleeve is resisted by a spring 439 disposed about shaft 426 beneath yoke 432, and acting in compression between a shoulder 440 on the sleeve and a washer or abutment 441 slidable on the shaft and held against axial movement by means of lock-nuts 442—442 threaded thereon. Adjusting the nuts will accordingly change the spring pressure and the resultant position of the parts for any given speed.

It is desirable for convenience in operating the dial 415 that the axial movement of sleeve 423 be proportional to the logarithms of the various speeds at which the apparatus is run, and this may be approximated by choosing suitable values for weights 435, and spring 439, together with suitable lengths for arms 433 and links 437. Correction may be effected in various ways if necessary or desirable, for example a yoke 443 may be

fixed on shaft 426 by means of lock-nuts 444—444 or the like, and may carry arms 445—445 pivoted thereto by means of pins 446—446, the arms carrying weights 447—447, preferably similar to weights 435—435, and the arms having downward extensions 448—448 provided with rolls 449—449 engaging cam portions 450—450 fixed with and extending from arms 433. At any speed at which the machine is to be used arms 445—445 will take substantially the positions shown with rolls 449 in contact with cam portions 450. Increases in speed above this minimum will tend to cause outward movement of both weights 435 and 447, but the parts are so proportioned that the force of weights 435 overcomes that in weights 447, the former acting through cam portions 450 and extensions 448 to force weights 447 downwardly and inwardly against the centrifugal force tending to move them outwardly. This force accordingly opposes the upward movement of weights 435 and their connected parts including sleeve 423, and consequently modifies the response of the apparatus to speed changes. The exact effect of this correction may be readily determined when the apparatus is constructed by choosing the proper contour of cams 450 in accordance with the values of the weights 447 and 435, while taking into account the lengths of the arms and the angles thereof relative to shaft 426 in the various positions. The device can readily be arranged in this manner to give a true logarithmic movement of sleeve 423 within substantially any limits of accuracy desired. Lock nuts 431 and 444 permit adjustments of the positions of yokes 432 and 443 to obtain the correct relation between cam portions 450 and rolls 449.

Shaft 426 drives through bevel gears 452 and 453 a shaft 454 journaled in a bearing 455 supported in head-stock 417, the shaft being also journaled in a sleeve 456 also supported from the head-stock by means of a web portion 457, the sleeve serving to support certain other elements as will be presently apparent. Shaft 454 has a head portion 454a against which disk 413 is fastened by screws or the like 458, a pilot portion 459 serving to accurately center the disk when it is applied to the shaft. An opening 460 in disk 413 permits observation of the light of a discharge tube 461 in the manner above described in connection with indicator 11.

Sleeve 423 actuates dial 415 as follows: Collars 428 and 429 engage a fork or other follower member 462 carried by an arm 463 suitably fixed with a rod 464 slidably supported in suitable guides 465 and 466 carried respectively by head-stock 417 and web 457, the rod preferably sliding in a direction parallel to the movement of sleeve 423 and terminating at its upper end in a rack portion 467 engaging a gear 468 formed on or fixed with a hub portion 469 journaled on the exterior of above mentioned sleeve 456. Hub 469 carries above mentioned dial 415 through an arm 470 in the present instance of sufficient stiffness to carry the dial and maintain it in correct relation to hub 469 without other bracing. The above described logarithmic movement of sleeve 423, through the above outlined mechanism will cause true logarithmic movement of dial 415, and it is to be understood that various well-known expedients such as ball, or other anti-friction bearings are contemplated as applicable to the various joints and bearings of the device without departing from the scope and spirit of the invention, but since these could be readily applied by one skilled in

the art, to avoid undue complication they are not shown in the present drawings.

Tube 461 is supported in a stationary housing 471 fixed with above mentioned sleeve 456, the housing being clamped thereon by means of a bolt or the like 472. Tube 461 may be supported in the housing by suitable means such as clips 473, and one terminal lead 474 is connected with housing 471 by means of a screw or the like 475, while the other terminal lead 476 extends backwardly through an opening 477 in housing 471 and connects through a terminal plug 478 with a coil 479 preferably similar to above described coil 213. The elements of the remainder of the circuit of tube 461 correspond to the diagram of Fig. 20. Owing to the peculiar construction of the dial 415 with its hub 469 and single arm 470, substantially a complete revolution of the dial may be performed without interference with lead 476, and more than this is never desirable in dial 415. Housing 471 carries at its forward extremity a flange or dial portion 480 preferably carrying two scales 481 and 482, scale 481 reading angles against opening 460 in the manner above described, and scale 482 reading against an index 483 on dial 415, the index moving with the dial and indicating the speed of the work piece in revolutions per minute or other convenient units.

For diffusing the light from tube 461 a translucent member 484 is supported in housing 471 against a rim 485, the member being held in place by suitable means such for example as a ring 486 of spring wire or the like seated in a suitable groove in the housing. Dial 416 is held 35 against the front of a casing 487, preferably formed as a part of head-stock 417, by means of a spacer or washer 488 against which bears a transparent closure member 489 held in turn by a ring or frame 490 fixed on the casing by suitable means such as screws 491, the closure serving to protect the mechanism from dirt and to eliminate danger from the moving parts thereof.

The operation of the above described apparatus is generally similar to that described in connection with indicator 11. The operator operates the machine at the desired speed as indicated by index 483, and tests each journal of the work piece, locating the angular position at which deflection occurs, and notes the force necessary to counteract it as indicated by grip 12. With the work piece rotating under these conditions he finds this value on scale 416, and reads the value on scale 415 opposite the value just found on scale 416. This value will be the moment of the unbalanced weight in the work piece causing the deflection at that particular journal, and it is to be set up on dial 234 for future reference, and the next journal tested. If the speed unavoidably varies between the tests, the moment determinations will not be affected, since dial 415 will shift sufficiently to compensate for the change in speed. Any lag in the electrical or other parts of the angle indicating mechanism is corrected by movement of sleeve 423 in the same manner as in above described indicator 11, slot 425 being shaped to retard shaft 426 correct amounts in response to the axial movements of the sleeve. No calculations are necessary on the part of the operator to determine the moments of the unbalanced weights, and, knowing the moments, the operator may readily determine the weight of material to be removed from or added to the work piece at any convenient distance from the axis in order to achieve correct balance. Con-

siderable calculation and possibility of error is eliminated by this apparatus.

A modified arrangement for obtaining a true logarithmic movement of the calculating mechanism above described is shown in Fig. 33. In this device a spring 492 replaces spring 439, and it is formed of a suitable diameter or it may be of a non-uniform diameter, increasing toward one end as shown at a rate predetermined in accordance with the characteristics of the resistance desired. As a spring of this type is loaded the larger coils collapse successively against each other or a base as the pressure increases, and the effective length of the spring is decreased. By suitably shaping the spring a rate of increase 15 in stiffness can be provided which will exactly balance the increasing centrifugal force in weights 435 as the speed increases while permitting movement of sleeve 493 which is proportional to the logarithms of the changes in speed. Weights 447, cam portions 450, and their connected parts are not required in this structure. The operation of this embodiment is otherwise the same as that just described. Other expedients are contemplated for obtaining the 20 logarithmic movement of the sleeve 423, and it is to be understood that the invention is not limited to the specific structure disclosed, or in fact in any manner except as defined by the annexed claims.

The above being a complete description of my novel apparatus for testing and correcting work pieces for unbalance, what is claimed as new and desired to be secured by Letters Patent of the United States is:

1. In a balancing machine including means for supporting a work piece for rotation under conditions approximating normal operation thereof, and means for rotating said piece, the combination of a bearing having a stationary portion contacting said work piece and a movable portion contacting said work piece and permitting deflection thereof away from said stationary portion under centrifugal forces developed in said piece by rotation of unbalanced weight therein, said movable portion being disposed to be moved by such deflections, and mechanism arranged to resist movement of said movable portion, and arranged to indicate the force necessary to substantially prevent deflection of said work piece and movement of said movable portion.

2. In a machine for performing dynamic balancing including means for supporting a work piece under conditions approximating normal operation thereof, means for rotating said piece, and means for indicating the position of unbalanced weight in said piece, the combination of means for actuating said indicating means including supporting means for permitting deformations of said work piece under centrifugal forces developed by rotation of unbalanced weight in said work piece, including a plurality of bearings each having a fixed portion contacting said work piece and a movable portion contacting said work piece and arranged to be moved by deformations thereof away from said fixed portion, and means actuated from movement of one of said movable portions arranged to operate said indicating means substantially at the instant movement of said movable portion takes place.

3. In a balancing machine including means for supporting a work piece for rotation under conditions approximating normal operation thereof, means for rotating said piece, and

- means for indicating the position of unbalanced weight in said piece, the combination of a bearing having a fixed portion contacting said work piece and a movable portion contacting said work piece and permitting deflection thereof under centrifugal forces developed in said piece by rotation of unbalanced weight therein, said movable portion being arranged to be moved by such deflections, and a pair of electrical contacts controlled by movements of said movable portion, and connected in circuit to actuate said indicating means.
4. In a balancing machine including means for supporting a work piece for rotation under conditions approximating normal operation thereof, means for rotating said piece including a power source, said supporting means including a bearing having a rigid supporting portion and a movable portion permitting deflection of said work piece away from said rigid portion under centrifugal forces developed therein by rotation of unbalanced weight in said work piece, the combination of deflection indicating means comprising an electric circuit controlled by movements of said movable portion, a generator driven from said power source and connected for supplying energy to said circuit, a rotative member synchronized with said work piece and operative to indicate the position of said work piece at the time deflection thereof occurs, and a light connected with said circuit and energized from said generator in response to movements of said movable portion, and positioned to illuminate said rotative member.
5. In a bearing element for a balancing machine the combination of a frame and a plurality of plungers disposed radially about a work piece supported in said element, work piece engaging members on said plungers and arranged to support said work piece for rotation in said element, one of said plungers being yieldable in the direction of its length, all of said plungers being adjustable in the direction of their lengths, and certain of said plungers being arranged to be rigidly fixed with said frame for supporting said work piece against movement except in the direction of said yieldable plunger.
6. In a bearing element for a balancing machine the combination of a frame, and a plurality of plungers disposed radially about a work piece supported in said element, work piece engaging members on said plungers, said plungers being adjustable in the direction of their length, and arranged to be rigidly fixed with said frame, one of said plungers having a yieldable portion disposed to be moved by deflections of said work piece, electrical contact means including a lever, a fixed fulcrum for said lever, and actuating means for said lever operated from said yieldable portion, said actuating means being engageable with said lever alternatively at one or the other side of said fulcrum whereby deflection of said work piece may actuate said lever in the desired direction.
7. In a balancing machine the combination of a head-stock, a spindle in said head-stock, means for rotating said spindle, and means on said spindle for rotating a work piece, a rotative indicator mounted on said head-stock, and connections for rotating said indicator from said spindle in synchronism with said work piece, said connections including a speed responsive device arranged to change the angular relation between said spindle and said indicator in accordance

with the time-lag characteristics of said indicator.

8. In a balancing machine the combination of means for supporting a work piece in operative position, means for rotating said piece while so supported, means permitting deformation of said work piece under centrifugal forces developed by unbalanced weight in said work piece, synchronous means actuated by such deformation and operative to indicate the angular position of said work piece in which said deformation occurred, a speed responsive device driven in fixed relation to said work piece and including a part arranged to move in response to speed changes distances proportional to the logarithms of such changes, a first logarithmic scale fixedly supported on said machine, a second logarithmic scale movably supported adjacent said first logarithmic scale, and connections from said part arranged to move said second logarithmic scale distances proportional to the movement of said part.

9. In a bearing element for a balancing machine the combination of a frame, and a plurality of plungers carried by said frame and disposed radially about a work piece supported in said bearing element, work piece engaging members on said plungers, one of said plungers being adjustable in the direction of its length, and arranged to be rigidly fixed with said frame, and another plunger having a yieldable portion disposed to be moved by deflections of said work piece, a lever, a fulcrum for said lever, connections from said yieldable portion to said lever adjacent said fulcrum, and electrical contact means connected with said lever remote from said fulcrum and actuated therefrom, whereby slight movement of said yieldable portion will produce appreciable movement of said contact means.

10. In a machine for performing dynamic balancing including means for supporting a work piece under conditions approximating normal operation thereof, and means for rotating said piece, the combination of a bearing having a stationary portion contacting said work piece and a movable portion contacting said work piece and permitting deflection thereof away from said stationary portion under centrifugal forces developed in said piece by rotation of unbalanced weight therein, said movable portion being disposed to be moved by such deflections, mechanism arranged to resist movement of said movable portion, and arranged to indicate the force necessary to substantially prevent deflection of said work piece and movement of said movable portion.

11. In a balancing machine including means for supporting a work piece for rotation under conditions approximating normal operation thereof, means for rotating said piece, and means for indicating the position of unbalanced weight in said piece, the combination of a bearing having a fixed portion contacting said work piece and a movable portion contacting said work piece and permitting deflection thereof under centrifugal forces developed in said piece by rotation of unbalanced weight therein, said portion being arranged to be moved by such deflections, a pair of electrical contacts controlled by movements of said movable portion, and connected in circuit to actuate said indicating means, and motion multiplying means interposed between said movable portion and said electrical contacts for insuring adequate movement of said contacts with very slight movement of said portion.

12. In a balancing machine including means

- for supporting a work piece in operative position, means for rotating said piece, and means permitting deflection of said piece under centrifugal forces developed by unbalanced weight in said 5 work piece, the combination of indicating means for said unbalanced weight including a rotative element, means for driving said element from said machine in synchronism with said work piece, and a speed responsive device interposed 10 in said driving means and arranged to synchronize said rotative element in various angular relations to said work piece in accordance with various speeds of rotation thereof, whereby lag characteristics of said indicating means may be automatically compensated to avoid error in the indications thereof.

13. In a balancing machine including a bearing element for supporting a work piece to be

balanced and having a movable portion arranged to be actuated by deflections of a work piece supported in said element, and means for rotating said work piece supported in said element, the combination of indicating means including an 5 electric circuit arranged to be controlled by movement of said movable portion caused by unbalanced weight in said work piece, a discharge tube energized by said electric circuit, and a rotative element enclosing said discharge tube and having 10 an opening illuminated by said tube and so located that light from said tube may proceed therethrough directly to an observer when said tube is energized, and mechanism arranged to rotate said rotative element in synchronism with 15 the rotation of said work piece.

JOHN LEONARD TAYLOR.
